UNITED STATES PATENT OFFICE.

DANIEL B. TAMAGNO, OF NEW YORK, N. Y., ASSIGNOR TO LYDIE TAMAGNO, OF NEW YORK, N. Y.

CAN-CLOSURE.

1,140,295.

Specification of Letters Patent. Patented May 18, 1915.

Application filed August 2, 1913. Serial No. 782,603.

To all whom it may concern:

Be it known that I, DANIEL B. TAMAGNO, a citizen of the United States of America, residing in the borough of Manhattan, city, 5 county, and State of New York, have invented a certain new and useful Improved Can-Closure, of which the following is a specification.

This invention relates to a telescoping 10 pouring spout which in depressed position forms a tight closure for the can.

The axis of the spout may be disposed at an angle, as hereinafter appears, and, being 15 preferably placed in the cover at one corner of the can, it is possible to pour from the spout substantially the entire contents of the can.

In the accompanying drawing: Figure 1 is 20 a plan view showing one angle or corner of a can: Fig. 2, a vertical longitudinal section: Fig. 3, a section indicated by the line A, B, of Fig. 2: Fig. 4, a detailed transverse section on the line C, D, of Fig. 2. Fig. 5, a detailed longitudinal section showing a slight modification: and Fig. 6, an elevation thereof.

1 indicates the side wall of a can and 2 the top thereof. Formed in the top is a 30 circular aperture 3 closed by a cover disk 4 which has a depression 5 to receive a hinged handle or draw loop 6 and also an aperture to receive the pouring spout and associated part. This aperture is, in the 35 preferred construction illustrated, rectangular in cross section. On the under side of the disk 4 and surrounding the aperture therein is a correspondingly shaped tube 8 closed at the bottom 9 and having a port 10 on the side adjacent the angle or corner 40 of the can and a smaller vent port 11 in the opposite wall. This tube is fitted to the under side of the flat part of the disk 4 and conformed to the under side of the depression 5 and is secured thereto by solder 12 so as 45 to form a hermetically sealed joint. In forming the port 10, which is rectangular, a surrounding edge of the stock of the square tube 8 is thrown inwardly, the flange so formed being marked 13. Above the flange 50 at the upper side of the port 10 is the projecting edge 14 of the cover disk 4; and below the flange, at the lower side of the port, the stock of the tube 8 is set inward, as at 15, to form a transverse rib. In the 55 space surrounding the flange 13 of the port 10

is set a flat rectangular packing or gasket 16 which is firmly held in position by the parts named and by contact with the two walls of the tube 8 that are at right angles to the wall in which the port is formed. This 60 packing is of appropriate material and of a thickness somewhat greater than the depth of the flange 13. Inside of the tube 8, opposite the side in which the port is formed, is the vent-opening 11 around which the 65 stock of the tube is turned inwardly to form an interior flange which may be circular or rectangular. Surrounding the flange of the vent-opening is a flat packing 17 held in position by said flange and disposed between 70 it and the adjacent bottom face of the covered disk 4 and supported at its edges by the adjacent side walls of the tube 8.

Fitted to slide in tube 8 is a telescoping 75 pouring spout 18 in close sealing relation to the oppositely disposed packing and having at its upper edge the hinged handle 6. The bottom of the telescoping spout which, when in depressed position, rests upon the bottom 9 of the tube 8 is formed with flanges 19, 20, 80 at least upon the opposite sides in which respectively are the port 10 and vent 11: and the bottom of the telescoping spout 18 is inset or countersunk, as shown at 21. Immediately above the bottom or floor of this 85 inset on one side is a port 11' adapted to register with the vent 11; and, on the opposite side, a port 10' adapted to register with the port 10. The floor of the inset 21 is inclined from the vent wall of the spout to the 90 opposite wall containing the port 10'. When the spout is drawn out, as indicated in dotted lines, its outward position is determined by abutment of flange 20, for instance, against the inset rib 15 in the outer tube 8 95 and, when so positioned, the port 10' is coincident with the port 10 and the port 11' is coincident with the vent-opening 11.

Figs. 5 and 6 indicate slight modifications, 100 that is to say, instead of the rib 15 being formed as shown in Fig. 2 by an inset having double parallel walls, it is made by forming an offset 22. On the vent side of the tube 8 there are similar offsets 23, 24 105 both above and below the inturned flange surrounding the vent-opening 11. The opposite walls of the sliding or telescoping spout thereupon have flat packings 16, 17 and are held out of contact with the inner surfaces of the opposite walls of the tube 8 in which 110

- the packings are set. The two other or transverse walls of the sliding or telescoping spout may run in contact with the corresponding walls of the tube 8. The flanges 5 19, 20, which may be placed on all four sides of the sliding spout at its inner end, fit the interior of the tube 8 and cause the spout to slide in a right line thereby preventing uneven strains or pressures upon the packings.
- 10 The walls, both of the outside fixed tube 8 and the interior telescoping or sliding spout, have more or less elasticity which facilitates an accurate fit of the packing surrounding the port 10 and that surrounding the vent 15 with the walls of the spout. When, after pouring, the can is returned to upright position, any material remaining in the spout will be directed by the floor of the inset 21 through the ports 10', 10 to the interior of the can after which the spout may be pressed down into innermost position.

20 The material of which this structure is made may be varied. For liquid contents, such as varnish and oil, it is preferably 25 made of sheet metal such as ordinary can stock but since the can may receive a great variety of materials in either granular or liquid form, it is apparent that quite a variety of materials may be used in the construction of the can. Where necessary, suitable adhesives or other means of fastening 30 may be employed instead of solder.

I claim:

- 35 1. A can closure comprising a tube extending into the can from the top thereof, a port in one side thereof adjacent the top of the can, packing surrounding the port and held in fixed relation thereto by inset ribs or flanges, a telescoping pouring spout fitting within said tube, having a port 40 adapted when the spout is drawn out to register with the port in the fixed tube, the wall of the spout in which said port is located moving in intimate contact with said packing, said spout also having a bottom or 45 floor which when the spout is drawn out is substantially opposite the bottom edge of the two said ports.
2. A can closure comprising a tube ex- 50 tending into the can from the top thereof, a port in one flat side thereof adjacent the top of the can, a flat packing surrounding the

port and held in fixed relation thereto by inset ribs or flanges, a telescoping pouring spout fitting within said tube, having in a 55 flat side a port adapted when the spout is drawn out to register with the port in the fixed tube, the wall of the spout in which said port is located moving in intimate contact with said packing, said spout also having a bottom or floor which when the spout is drawn out is substantially opposite the bottom edge of the two said ports.

3. A can closure comprising a tube extending into the can from the top thereof 60 and which is rectangular in cross section, a port adjacent the top of the can in one flat wall of the tube and a vent substantially opposite said port in the opposite flat wall of the tube, flat packings surrounding the port 65 and vent, means on the tube for locking or holding the packings in position, and a telescoping pouring spout having flat walls slide- 70 able within the tube in contact with the packings and provided with port and vent 75 openings adapted to align with the port and vent of the tube when the spout is withdrawn for pouring.

4. A can closure comprising a rectangular tube extending into the can from the top 80 thereof, a port in one of the flat walls of the tube adjacent the top of the can and a vent in the tube substantially opposite said port, packings surrounding the port and vent, means in the tube for holding the packings 85 in position, a telescoping pouring spout slide- able within the tube and having opposite flat walls that run in intimate contact with the packings surrounding the vent and port and having corresponding vent and port 90 openings adapted to be brought opposite said port and vents when the spout is withdrawn for pouring, said spout being otherwise closed except at its mouth and having a bottom or floor closely adjacent the lower 95 edge of the port-opening therein and inclining downwardly toward said port.

In testimony whereof, I have hereunto subscribed my name.

DANIEL B. TAMAGNO.
